United States Patent Office

Des. 205,741
Patented Sept. 13, 1966

205,741

HUMIDIFIER

Leonard L. White, 19504 Stansbury, Detroit, Mich., and
James H. McNeiece, 200145 Woodhill Drive, North-
ville, Mich.

Filed Aug. 2, 1965, Ser. No. 86,390

Term of patent 14 years

(Cl. D62—4)

FIG. 1

FIG. 2

FIG. 3

FIG. 4

FIG. 5

FIG. 6

FIGURE 1 is a front perspective view of a humidifier showing our new design;

FIGURE 2 is a side elevation of the right side of the humidifier of FIG. 1;

FIGURE 3 is a front elevation thereof;

FIGURE 4 is a top plan view thereof;

FIGURE 5 is an elevation of the left side thereof; and

FIGURE 6 is a bottom plan view thereof.

The dominant features of our design reside in the portions shown in full lines.

We claim:

The ornamental design for a humidifier, as shown and described.
